UNITED STATES PATENT OFFICE.

PAUL R. COLLIER, OF PHILADELPHIA, PENNSYLVANIA.

DESIGN FOR A RECEPTACLE-PLUG.

58,019.

Specification for Design.

Patented May 31, 1921.

Application filed September 30, 1920. Serial No. 413,922. Term of patent 7 years.

To all whom it may concern:

Be it known that I, PAUL R. COLLIER, a citizen of the United States, and a resident of Philadelphia, Wissahickon, in the county of Philadelphia and State of Pennsylvania, have invented a new, original, and ornamental Design for a Receptacle-Plug, of which the following is a specification, ref-

erence being had to the accompanying drawing, forming part thereof.

The figure is a plan view.

I claim:

The ornamental design for a receptacle plug substantially as shown.

PAUL R. COLLIER.
